FIG-3

Cassie R. Moses INVENTOR.

FIG-2

BY

Curtis D. Bush ATTORNEY

UNITED STATES PATENT OFFICE

CASSIE B. MOSES, OF DAVENPORT, IOWA

UMBRELLA

Application filed April 11, 1929. Serial No. 354,347.

My invention relates to improvements in umbrellas.

The objects of my invention are to provide a substantial umbrella which can be so cheaply constructed as to be available for advertising purposes or for sale at very low prices, and which will withstand a moderate amount of rain.

I attain these objects by the means illustrated in the accompanying drawings, in which,—

Figure 1 is a vertical section on the middle line of an umbrella constructed in accordance with my invention;

15 Figure 2 is a cross-section on the line 2—2 of Figure 1;

Figure 3 is an enlarged sectional detail showing the slide and spring for fastening same, but for clearness omitting the ribs.

20 Similar numbers refer to similar parts throughout the several views.

My umbrella comprises a handle, 1, in tubular form and preferably formed from a tube of pasteboard or some fibrous material, 25 although any tubular material of sufficient strength and lightness may be used.

The cover, 2, is preferably composed of a circular sheet of flexible, tough paper which may be treated with water-proofing material 30 if desired. At the center of the cover upon the upper face thereof, I re-enforce the cover by gluing thereto by water-proof glue or otherwise suitably attaching thereto, a circular piece of cloth, 8, or other strong fibrous material, cutting same into sectors, 17, which may be pushed down into the upper end of the tube, 1, and secured therein by a plug, 9, which may be glued or otherwise suitably secured in the upper end of the tube, 1, and

40 has a head which overlaps the upper end of the tube, 1. If desired, a similar piece of cloth or other re-enforcing material, 7, may be similarly attached to the under side of the cover with its inner edges extending down into the upper end of the tube, 1.

The plug, 9, and the re-enforcing strips, 8 and 7, are preferably attached to their adjacent parts by a water-proof glue or similar substance which will not become loose 50 when wet with water.

Ribs, 3, preferably composed of thin, flat strips of wood, are united to the under side of the cover, 2, by water-proof glue or other suitable means, and their inner ends are additionally secured by the re-enforcing strip, 7. 55

Braces, 4, have their upper ends attached to the lower face of the ribs, 3, preferably by strips of cloth, 5, which are secured by water-proof glue or other suitable means to the upper ends of the braces, 4, and to the intermediate portion of the ribs, 3. The lower ends of the braces, 4, are similarly secured to a sleeve, 10, by strips of cloth or other suitable material, 6, and glued or otherwise united thereto. 60

65 Any suitable material, either metal or fibrous, may be used for the sleeve, 10, but I prefer to construct it in the form of a pasteboard tube, as stock pasteboard tubes can readily be obtained and cut to the desired length, and will have sufficient strength to last as long as a single umbrella of this type is expected to be used.

70 Two holes, 15 and 16, are formed in the side of the tube, 1. Holes 13, and 14, are also formed in the sleeve, 10, and a spring, 12, preferably of spring wire, is secured to the sleeve, 10, by being passed through the hole, 13, and re-bent upon the upper end of the sleeve. The lower end of the spring has 75 a re-bent portion, 12', which is adapted to enter the holes, 14, 15 and 16, whenever registering therewith and the extreme lower end of the spring is preferably bent outwardly as shown in Figure 3, so as to allow the easy 80 insertion of the end of a person's thumb under it for the purpose of pulling it out of the hole, 15, or the hole, 16. 85

90 In the construction of my device, the sectors, 17, are bent downwardly upon the line 18 and secured in the upper end of the tube, 1, by the plug, 9, the strips, 7 and 8, first having been fastened to the cover, 2, and the ribs, 3, having been attached thereto. The braces, 4, are then attached to the cover as described, 95 and the slide, 10, placed upon the handle, 1, and the lower ends of the braces, 4, fastened thereto. The spring, 12, is preferably placed upon the slide, 10, before the slide is placed upon the handle, 1. The lower end of the 100

handle, 1, is preferably closed by a rounded plug, 11, which may be glued or otherwise suitably secured therein.

If it is desired to use these umbrellas for advertising purposes, any suitable advertisement may be printed thereon and when desired to use them without advertising, they are preferably made of various attractive bright colors.

These umbrellas can be constructed at a price which will make them available to give away for advertising purposes and also may be available for sale at a low price at various ocean and lake beaches where some kind of a sunshade is required. They also make an excellent protection from light rains for use in connection with convention parades and things of that kind where large numbers of people might desire to purchase a cheap umbrella to be thrown away when they get through with it for that particular occasion.

I do not restrict my cover to paper, as cloth or other suitable fibrous material may be used and when the cover is strong enough, the central portion thereof may be cut into sectors and bent down and secured in the tube as described above without the re-enforcing strips, 7 and 8, or with only one of them.

I do not restrict my invention to the precise form of attaching the braces to the ribs and to the slide shown in the drawings, as same may be attached by securing the strips of fibrous material that form the hinges to the ribs and braces by staples or other means, or other forms of hinges such as hinges formed integral with wire staples may be used to connect them, but I prefer the form shown on account of its simplicity and the ease of attaching same.

The ribs are preferably formed to extend a little beyond the cover to protect the cover, but when desired, they may be made a little shorter than the cover and the edge of the cover fringed or otherwise ornamented without departing from the spirit of my invention.

I claim:

1. In an umbrella, a hollow handle and a cover united thereto by a plug which wedges the central portion of the cover into the upper end of the handle and secures same therein.

2. In an umbrella, a hollow handle, a cover, a re-enforcing strip centrally attached to the cover having sectors at the center thereof turned downwardly and secured in the upper end of the handle.

3. In an umbrella, a hollow handle, a cover, a re-enforcing strip centrally attached to the cover having sectors at the center thereof turned downwardly and secured in the upper end of the handle by a closely-fitting plug.

4. In an umbrella, a hollow handle, a cover, a re-enforcing strip centrally attached to the cover having sectors at the center thereof turned downwardly and secured in the upper

end of the handle by a closely-fitting plug glued within the upper end of the handle.

5. In an umbrella, a hollow handle, a cover, a re-enforcing strip centrally attached to the cover having sectors at the center thereof turned downwardly and secured in the upper end of the handle by a closely-fitting plug secured in the upper end of the handle, said plug having an enlarged head.

6. In an umbrella, a hollow handle, a cover, a re-enforcing strip centrally attached to the cover having sectors at the center thereof turned downwardly and secured in the upper end of the handle by a closely-fitting plug glued in the upper end of the handle, said plug having an enlarged head.

7. As an article of manufacture, an umbrella comprising a tubular pasteboard handle, a cover with central re-enforcements secured to the upper end of the handle by a plug which wedges portions of the cover into the end of the handle, and means for raising and lowering the cover and securing it in either the raised or lowered position.

8. In an umbrella, the combination with a hollow handle, of a plug fitted into the upper end thereof, a cover, a re-enforcing piece united to the cover at the center thereof, with sectors of the cover and re-enforcing piece entered into the upper end of the handle and secured therein by the plug.

9. In an umbrella, a tubular pasteboard handle, a cover, a re-enforcing strip centrally attached to the cover, and sectors of the cover and re-enforcing strip at the center thereof turned downwardly into and secured in the upper end of the handle.

In testimony whereof she affixes her signature.
